UNITED STATES PATENT O

YOLE SAYNISCH, OF NEW YORK, N. Y.

WASHABLE CORSET.

1,171,256.

Specification of Letters Patent.

Patent

Application filed September 17, 1915. Serial No. 51,142.

To all whom it may concern:

Be it known that I, YOLE SAYNISCH, a subject of the King of Italy, and a resident of the city of New York, borough of Manhattan, in the county and State of New York, have invented a new and Improved Washable Corset, of which the following is a full, clear, and exact description.

My invention relates to washable corsets, and the object thereof is to provide a simple, inexpensive and sanitary corset which is provided with removable corset steels whereby the fabric can be washed as any other garment.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a perspective elevation of a corset embodying my invention; Fig. 2 is an enlarged fragmentary view of the front edge of the corset showing the steel locked within the corset fabric; Fig. 3 is a similar view of the front edge of the corset, showing the front steel partly out of the pocket which is adapted to accommodate the steel and in which the steel is adapted to be locked; Fig. 4 is a cross section on line 4—4, Fig. 2; Fig. 5 is a similar cross section on line 5—5, Fig. 3; Fig. 6 is a section on line 6—6, Fig. 2; and Fig. 7 is a fragmentary rear elevation of the corset partly broken away to show the details of construction.

The subject matter of this invention is an improvement over my Patent No. 1,147,555, issued July 20, 1915.

Referring to the drawings, the washable corset fabric 8 at each side edge thereof is provided with a pocket 9 extending substantially through the length of the longitudinal edge. Each of the pockets has a transverse opening or slit 10 adjacent the upper end of the pocket. Suitably-spaced openings are also provided in the free edge of each of the pockets. A steel 12 having suitably-spaced lateral projections 13 is fitted into each pocket through the slit 10. The width of the pocket is substantially equal to the total width of the steel and projection. Each of the projections 13 of the

steel has a depending from the steel proper by the width of which is sl the thickness of the front edge of the pocket openings 11 is slightly width of the projections that the said projections trude through the openi the projections of a stee alignment with the openi engaged by the steel. It the projections 13 of th similarly to the openings As the projections 13 are through the openings 11 thereof will pass over the openings 11 and thereby from receding from the pockets; that is to say, gaged in a pocket, as sl and 7, the engagement with the front edge of t the steel within the pock ward the rear wall there

To facilitate the manip when inserting or remov the corresponding pocket totally secured to the upp The upper edge of the s shown at 17, to coöpera catch 18 on the link, wh be maintained at differen inserting or removing a Fig. 3, the link 16 must as indicated in Fig. 3. jections 13 of a steel are ment with the openings 1 ed bodily by applying p edge of the steel throug the corset. The notches can then be made to eng of the openings 11 eithe steel by means of the lin pulling on the projection truded through the poc will still project through the steel will be within t

By turning the link 16 through the slit and their position shown in dotted upper edge of the link against the top of the po the lower straight edge o the lower end of the pock force the bottom of the

portion 14 spaced a slot or notch 15, ightly greater than rset fabric at the t. The size of the greater than the 13 at the steels, so 13 will easily prongs 11 when all of 1 are brought into ings 11 of the pocket is self-evident that ie. steel are spaced 11 in the pockets. e made to protrude 1, the notches 15 e lower edge of the prevent the steel front edge of the 75 when a steel is enrown in Figs. 2, 3 of the notches 15 he pocket prevents et from moving to of. ulation of the steels sing the steels from s, a link 16 is pive end of the steel. 85 steel is notched, as te with a resilient erely the link can t positions. When steel as shown in 90 be in the position When all the pro brought in a line 1 the steel is shift pressure to the rear 95 h the material of of the projections ge the lower edge r by lowering the k 16 or by simply 100 s which have proket. The link 16 the slit 10, while he pocket. to enter the pocket 105 1 forcing it to the line in Fig. 2, the will be brought ocket, thus forcing f the steel against 110 et. This will also notches 15 against

the corresponding lower edges of the openings 11. The engagement of the lower edge of the steel with the bottom and the upper edge of the link with the top of the pocket 5 will prevent any longitudinal displacement of the steel within the pocket, while the engagement of the notch with the front edge of the pocket prevents any lateral displacement of the steel; consequently the steel is 10 positively locked within the pocket from any displacement.

The coöperating front and rear steels have the usual fastening devices provided on their 15 projections 13. The corset fabric has rear flaps 19 adjacent the front edge of each pocket for protecting the body from the 20 projections 13 of the steel. Narrower front flaps 20 are provided at the front edge of each pocket which extend only partly over the 25 projections 13 to cover the depending portions 14 of the projections, thus giving a neater appearance to the corset.

When a steel is to be removed from a pocket the link 16 is forced through the slit 10 by 25 applying pressure at the front edge of the pocket, as can be easily seen in Fig. 2. After forcing the link out of the slit 10 the same can be returned to its original position at the outside of the pocket. The steel 30 can then be pulled up within the pocket to bring the projections 13 in alinement with the corresponding openings 11. A pressure on the 35 projections will force them into the pocket, bringing the rear edge of the steel against the rear edge of the pocket. By pulling on the link 19 the steel can be pulled out of the pocket. When the steels of the corset are removed, as stated, the fabric can be easily washed as any ordinary garment.

40 I claim:

1. In a corset, a washable fabric body, front and rear steels each having notched, 45 spaced projections, said fabric having pockets at the longitudinal edges thereof each adapted to receive a steel with its projections, said pockets having openings in the edges thereof through which said projections of the steels are adapted to protrude, the notches of the projections being adapted 50 to engage the edge of a pocket at the openings, said projections of steels having the usual closure fastening means.

2. In a corset, a washable fabric body, front and rear steels having notched, space 55 projections, said fabric having pockets at the longitudinal edges thereof, each of said pockets having a slit adjacent the upper end thereof through which a steel with its projections may be inserted or removed 60 from the pocket, each of said pockets having openings in the edge thereof through

which the projections are adapted to protrude, the notches of the projections being adapted to engage the edge of the pocket at the openings, whereby the steel is prevented 65 from lateral displacement within the pocket, a link at the upper end of the steel for facilitating the manipulation thereof and adapted to engage the upper end of the pocket, whereby the lower end of the steel 70 is brought into engagement with the lower end of the pocket, thereby locking the steel from longitudinal displacement within the pocket.

3. In a corset, a washable fabric body, 75 front and rear steels each having spaced, lateral projections, said fabric having longitudinal pockets adjacent the longitudinal edges thereof, each pocket having a slit adjacent the upper end thereof through which a steel may be inserted in the pocket or removed therefrom with the projections thereof, each of said pockets having openings in the edge thereof through which said projections are adapted to protrude, each of said 80 projections having a longitudinal notch in proximity to the steel body for engaging the edge of the pocket at the lower end of the opening, a link at the upper end of the steel, and means for maintaining the link 85 at predetermined positions on said steel, said link being adapted to engage the upper end of the pocket, thereby forcing the lower end of the steel against the lower end of the pocket, substantially as and for the purpose 90 set forth.

4. A steel for corsets having spaced lateral projections, a link pivotally connected to one end of the steel, and means for locking the link in predetermined positions on 100 the steel, said steel having a longitudinal notch in each projection in proximity to the steel body.

5. In a corset, a washable fabric body having pockets at the longitudinal edges 105 thereof, a steel removably associated with each pocket, said steel having spaced, notched projections, said pockets having openings in the edges through which the projections are adapted to protrude, the 110 notches of the projections being adapted to engage the edge of a pocket, and means for locking the steel in its pocket, said projections of the steels having the usual closure fastening means.

In testimony whereof I have signed my name to this specification in the presence of two subscribing witnesses.

YOLE SAYNISCH.
